(57) CLAIM

The ornamental design for a lighter as shown and described.

DESCRIPTION

FIG. 1 is a front perspective view of a lighter in a closed mode showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is another front perspective view thereof in an opened mode;

FIG. 11 is another rear perspective view thereof;

FIG. 12 is the other front perspective view showing a block located thereon; and,

FIG. 13 is the other front perspective view showing the block located thereon in a different location.

The broken lines depict portions of the lighter that form no part of the claimed design.
